PAGE 3

FIGURE 1 is a left side elevational view of a tractor embodying our new design.

FIGURE 2 is a prospective view of the tractor shown in FIGURE 1, and taken generally from the right front side thereof.

FIGURE 3 is a prospective view of the tractor generally from the right rear side of the tractor.

FIGURE 4 is a prospective view of the tractor shown in FIGURE 1, taken generally from the left rear side of the tractor.

The dominant features of the design reside in the portion shown in full lines.

We claim:

The ornamental design for a tractor, substantially as shown and described.
